UNITED STATES PATENT OFFICE.

CARL J. FRID, OF STEGE, CALIFORNIA.

LIFE-PRESERVER.

1,131,227.

Specification of Letters Patent.

Patented Mar. 9, 1915.

Application filed September 22, 1913. Serial No. 791,241.

To all whom it may concern:

Be it known that I, CARL J. FRID, a citizen of the United States, residing at Stege, in the county of Contra Costa and State of California, have invented certain new and useful Improvements in Life-Preservers, of which the following is a specification.

This invention relates to improvements in life preservers and its object is to produce 10 a device of this class in which the entire body of the wearer is protected from the water.

Another object is to produce a device of 15 this class provided with air passages by means of which air is admitted to the wearer while he is in the water. Means for drawing off any water that may get into the device while in use are also provided.

With the foregoing and other objects in 20 view the invention consists in the combination and arrangement of parts to be hereinafter fully described in the following specification, pointed out in the claim and illustrated in the accompanying drawings 25 which form a part of said specification and in which—

Figure 1 is a front elevation of my improved life preserver. Fig. 2 is a vertical section through the air-admission compartment. Fig. 3 is a vertical section through 30 a portion of the device. Fig. 4 is a rear view of Fig. 3. Fig. 5 is a detail of the neck band. Fig. 6 is a sectional of the ventilator band. Fig. 7 is a section taken on 35 line 7—7 of Fig. 1. Fig. 8 is a section taken on line 8—8 of Fig. 1. Fig. 9 is a section taken on line 11—11 of Fig. 3. Fig. 10 is a view of half of the mask. Fig. 11 is a view of one of the locking clasps used. Fig. 40 12 is a section taken on line 12—12 of Fig. 1.

Like reference characters indicate corresponding parts throughout the several views.

My device comprises the water proof suit 45 1 which buttons down the front by means of the screw-buttons 2 which join the overlapping edges of the garment. The suit is formed with the usual sleeves 3, 3 each of which is provided with a water tight wrist 50 band 4. The suit is further provided with water tight food pockets 5 in which pro-

visions may be stored for use while in the water and other food pockets 6 may be carried upon a connection between the suit and the water tight life belt 7 which is secured 55 by flexible connections 8 to the suit.

To the suit a water tight head piece 9 is secured by means of the removable mask 10 which connects it with the neck band 11 carried by the suit. A window or transparent 60 lookout 12 is provided in the head piece. To the top of the head piece a ventilator 13 is secured by means of a band 14 and within 65 said ventilator an air or water passage 15 is secured that connects with a water bag 16 disposed inside the suit 1 and provided with a water exhaust 17 extending out through the suit and by means of which the liquid contents of the bag may be emptied. The ventilator 13 is provided with apertures 70 18 to admit air and with downwardly inclined air passages 19 through which the air is led into said ventilator. In the water the wearer of the suit is kept in an upright position and through the air passages de- 75 scribed he will be supplied with air but it is possible that some water may enter through these passages also due to the motion of the sea and this water will be conducted through the passage 15 into the water bag 80 and back into the sea. To the feet of the wearer metallic ballast pads 20 are secured to insure upright position.

What is claimed is:—

In a life preserver, a water tight suit, a 85 floating baggage-carrying belt, encircling said suit and flexibly secured thereto, a head-piece for said suit, a ventilator opening downwardly and outwardly carried by said head-piece, a water bag arranged inside 90 said suit, a water passage connecting said water bag and the aforesaid ventilator, and water discharge means for said water bag.

In testimony that I claim the foregoing 95 as my own I have hereto affixed my signature in the presence of two subscribing witnesses.

CARL J. FRID.
